UNITED STATES PATENT OFFICE

EVERETT R. HUME, OF WEATHERFORD, OKLAHOMA

AMUSEMENT DEVICE

Application filed December 22, 1930. Serial No. 504,127.

This invention relates to amusement devices and has for an object the provision of a device which includes a number of horizontally and circularly movable seats mounted for swinging movement, together with means whereby the occupants of certain of the seats may manually operate the device and thus provide an amusement device which may be operated without cost for power.

Another object of the invention is the provision of novel means for adjusting the operating means to suit the occupants of the seats, so that the device may be conveniently operated by persons of all ages.

With the above and other objects in view, the invention further includes the following novel features and details of construction, to be hereinafter more fully described, illustrated in the accompanying drawings and pointed out in the appended claims.

In the drawings:

Figure 1 is a top plan view of the invention.

Figure 2 is a side view.

Figure 3 is an enlarged vertical sectional view taken through the standard, parts being broken away and shown in elevation.

Figure 4 is an enlarged fragmentary sectional view taken substantially on the line 30 4-4 of Figure 1.

Figures 5 and 6 are sectional views taken respectively on the lines 5-5 and 6-6 of Figure 4.

Figure 7 is an enlarged fragmentary view 35 partly in section and illustrating the operating gears.

Figure 8 is a view showing the bearing rings in separated relation.

Referring to the drawings in detail where- 40 in like characters of reference denote corresponding parts, the reference character 10 indicates a standard which may be of suitable construction, but which is shown as comprising a lower tubular section 11 and an upper tubular section 12, the latter telescoping within the former.

Mounted upon the upper end of the section 11 and surrounding the section 12 is a bearing member 13 which supports an annulus 14 through the medium of anti-friction devices

15. Extending radially from the annulus 14 are horizontally disposed arms 16, and swingingly secured to the outer ends of these arms in eyes 17 are supporting arms 18 for seats 19. These seats may be of any desired 55 construction and size, and are swingingly supported at the lower ends of the arms 18. Braces 20 connect the seats and the arms 16.

Secured to the outer ends of the arms 16 are the outer ends of inclined braces 21. The 60 inner ends of these braces are connected to an annulus 22 which surrounds the upper section of the standard and which operates on anti-friction bearings 23 supported by a bearing member 24 which is stationary with 65 the standard. A bottom plate 25 is secured to the annulus 22, while a similar plate 26 is secured to the annulus 14.

Extending outwardly from the standard 10 are shafts 27. The inner ends of these 70 shafts are supported upon spindles 28 which extend from bearing rings 29 and 30, surrounding the standard. One of the spindles 28 is carried by the lower ring 29 while the other spindle is carried by the ring 30. These 75 spindles form bearings for the inner ends of the shafts 27 and secured upon the inner ends of these shafts are pinions 31 which engage a ring gear 32. This gear surrounds 80 and is stationary with respect to the standard. A collar 33 which is secured to the standard acts to hold the parts in place. In addition the upper bearing ring has extending therefrom angle brackets 34 to which is 85 secured a cap 35, the latter forming a part of a gear housing, whose base is shown at 36. This gear housing is provided with 90 openings 37 for the passage of the shafts 27, and as these shafts are adapted to move about the standard, the housing will also move.

The outer ends of the shafts 27 have extending therefrom sleeves 38, and extending from these sleeves is a shaft extension 39 which is mounted for rotation in bearings 40. These bearings are supported upon spaced bars 41 whose opposite ends are secured to the supporting means for certain of the seats. The shaft extension 39 carries spaced crank arms 42 which, as shown in Figure 1 of the drawings, are positioned in advance of certain 95 100

of the seats so that the occupants of these seats may rotate the shafts after the manner of foot pedals. Rotation of the shafts will thus cause the pinions 31 to travel around the 5 ring gear 32 and operate the device.

The bearings 40 are adjustable upon the bars 41 and for this purpose the bearings are provided with wedge-shaped extensions 43 which are removably positioned within 10 spaced notches or depressions 44 provided along the upper edges of the bars 41. This will permit of positioning the bearings with respect to the seats and in accordance with the length of the legs of the occupants of the 15 seat. As this adjustment of the bearings will change the position of the shafts 27 with respect to the standard, this change of position is compensated for by the adjustability of the spindles 28 about the standard. Links 20 or stirrups 45 which extend downwardly from the bearings 40 act to prevent accidental disengagement of the extensions 43 from the notches 44.

The shafts 27 are connected with the shaft 25 extensions 39 through the medium of clutch members 46 and 47, the former being carried by the inner end of the shaft extension 39, while the latter is slidably and non-rotatably mounted upon the adjacent portion 30 of the shaft 27. The adjacent faces of the clutch members 46 and 47 are provided with ratchet teeth 48, whereby the shaft extensions 39 may rotate independently of the shafts 27 in one direction, but will be held 35 against independent rotation in an opposite direction. A spring 49 which is interposed between the clutch member 47 and the plug 50 in the end of the sleeve 37 acts to yieldingly hold the clutch member 47 engaged 40 with the clutch member 46. When the shafts are operated to move the device in one direction, the shaft extensions 39 will be locked to the shafts 27, but movement of the shafts 27 in an opposite direction will not affect 45 the shaft extensions due to the ratchet clutch just described. Danger of injury to the operators or riders from this cause will thus be prevented.

The invention is susceptible of various 50 changes in its form, proportions and minor 55 details of construction and the right is herein reserved to make such changes as properly fall within the scope of the appended claims.

Having described the invention what is 55 claimed is:—

1. In an amusement device, a vertically supported standard, arms extending radially from the standard and having their inner ends connected for movement about the 60 standard, seats swingingly supported at the outer ends of the arms, braces for said arms, horizontal shafts extending outwardly from the standard, a stationary ring gear mounted upon the standard, pinions secured to the 65 shafts and engaging the gear, bearings for

the outer ends of the shafts, spaced parallel bearing supporting bars secured to the seat supporting means and having spaced depressions in their upper edges, lugs carried by the bearings for removable engagement within the depressions to adjustably support the outer ends of the shafts, and crank arms at the outer ends of the shafts in advance of certain of the seats, whereby the shafts may be rotated to operate the device. 70

2. In an amusement device, a vertically supported standard, arms extending radially therefrom and having their inner ends connected for movement about the standard, 80 seats swingingly supported at the outer ends of the arms, horizontal shafts extending outwardly from the standard, rings rotatably supported upon the standard, means carried by the rings and engaging the inner ends of the shafts to rotatably support the same, a stationary ring gear mounted upon the standard, pinions secured to the shafts and engaging the gear, bearings for the outer ends of the shafts, and crank arms at the outer ends of the shafts in advance of certain of the 85 seats, whereby the shafts may be rotated to 90 operate the device.

In testimony whereof I affix my signature.
EVERETT R. HUME.
